DESIGN FOR A DRESS

Lise Abend Andors, New York, N. Y.

Application December 21, 1938, Serial No. 81,906

Term of patent 3½ years

To all whom it may concern:

Be it known that Lise Abend Andors, a citizen of the United States, residing at 1375 Broadway, New York, in the county of New York and State of New York, has invented a new, original, and ornamental Design for a Dress, of which the following is a specification, reference being had to the accompanying drawing, forming part thereof.

Fig. 1 is a front view of a dress showing my design; and

Fig. 2 is a rear view of the dress shown in Fig. 1.

I claim:

The ornamental design for a dress, substantially as shown.

LISE ABEND ANDORS.
